UNITED STATES PATENT OFFICE.

EDWARD P. WALTER AND HENRY C. WALTER, OF BRIDGEPORT, CONN.

METAL-PLANING MACHINE.

SPECIFICATION forming part of Letters Patent No. 293,289, dated February 12, 1884.

Application filed September 21, 1883. (No model.)

To all whom it may concern:

Be it known that we, EDWARD P. WALTER and HENRY C. WALTER, citizens of the United States, residing at Bridgeport, in the county 5 of Fairfield and State of Connecticut, have invented certain new and useful Improvements in Metal-Planing Machines; and we do hereby declare the following to be a full, clear, and exact description of the invention, such as will 10 enable others skilled in the art to which it appertains to make and use the same.

Our invention relates to certain novel and useful improvements in machines for planing metal, and has for its object to impart motion 15 from the driving-pulleys to the mechanism which effects the movements of the table by positive and uniform means, while at the same time the arrangement of the pulleys may be more convenient, and all unnecessary rattling 20 noise common to planers done away with; and with these ends in view our invention consists in the construction and combination of elements hereinafter fully and in detail explained, and then specifically designated by 25 the claim.

In order that those skilled in the art to which our invention appertains may more fully understand its construction and operation, we will proceed to describe the same in detail, referring by letters to the accompanying drawings, forming a part of this specification, in 30 which—

Figure 1 is a plan view, illustrating our improvement applied to a planer, such as is described in Patent No. 36,113, granted August 35 5, 1862, to William Sellers; and Fig. 2 a front elevation of the same.

Similar letters denote like parts in both figures of the drawings.

We will not enter into any description of the principles of construction and the operation of the machine proper, as this forms no part of our invention, and, moreover, is the same as in the patent above referred to. As 40 is set forth in said patent, motion is communicated to the table by means of a spirally-toothed pinion, A, upon a shaft, B, crossing the bed diagonally, said pinion gearing with

a rack in the table. This shaft we extend outward at the side of the machine, and arrange 50 on the extremity thereof a spur-wheel, C, which gears with a spiral pinion, D, on the shaft E. This shaft is journaled so as to extend transversely to the line of movement of the table.

The driving-pulleys may be arranged on any convenient portion of the shaft E, either on the same side of the machine, or one at each side, as desired.

The operation of our improvement is as follows: The shaft E receives motion from the pulleys and causes the spiral pinion D to gear with the spur-wheel C and operate the shaft B. The actuating of the shaft B by this means produces a result never before accomplished— 60 namely, a uniform positive movement of the table without any rattling whatever. We preferably arrange the shaft E at right angles to the line of movement of the table, whereby we are enabled to keep the pitch of the teeth 65 in the spur-wheel C and the angle of the helix on the spiral pinion D in a plane parallel with the shaft B, which of course is a great advantage. When the movement of the table is reversed there is no shock because the helix 70 on the spiral pinion always maintains a firm hold on the teeth of the spur-wheel.

Having thus described our invention, what we claim as new, and desire to secure by Letters Patent, is—

The combination, with a metal planer, having an obliquely-arranged shaft provided with a spirally-toothed pinion meshing with a rack in the table and a spur-wheel on its outer extremity, of a transversely-arranged driving-shaft, having a spirally-toothed pinion meshing with said spur-wheel, substantially 75 as shown and described.

In testimony whereof we affix our signatures in presence of two witnesses.

EDWARD P. WALTER.
HENRY C. WALTER.
